DESIGN FOR AN ILLUMINATING CAMERA STAND

Joseph L. Simpson, Los Angeles, Calif.

Application April 1, 1941, Serial No. 100,077

Term of patent 14 years

To all whom it may concern:

Be it known that I, Joseph L. Simpson, a citizen of the United States, residing at Los Angeles, in the county of Los Angeles, State of California, have invented a new, original, and ornamental Design for an Illuminating Camera Stand, of which the following is a specification, reference being had to the accompanying drawing, forming part thereof.

Fig. 1 is a three-quarter front perspective view of an illuminating camera stand, showing my new design.

Fig. 2 is a plan view thereof, the foot support being omitted from this figure for convenience of illustration.

I claim:

The ornamental design for an illuminating camera stand, substantially as shown and described.

JOSEPH L. SIMPSON.
